US0D1095471S

(12) **United States Design Patent** (10) **Patent No.:** **US D1,095,471 S**
(45) **Date of Patent:** **** Sep. 30, 2025**

(54) **SUSCEPTOR**

(71) Applicant: **NuFlare Technology, Inc.**, Kanagawa
(JP)

(72) Inventors: **Kunihiko Suzuki**, Shizuoka (JP);
Takuto Umetsu, Kamakura (JP)

(73) Assignee: **NuFlare Technology, Inc.**, Kanagawa
(JP)

(**) Term: **15 Years**

(21) Appl. No.: **29/888,125**

(22) Filed: **Mar. 28, 2023**

(30) **Foreign Application Priority Data**

Oct. 20, 2022 (JP) ..... 2022-022679 D
(51) **LOC (15) Cl.** **13-03**

(52) **U.S. Cl.**
USPC **D13/182**

(57) **CLAIM**

The ornamental design for a susceptor as shown and described.

DESCRIPTION

FIG. 1 is a perspective view of a susceptor showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

(Continued)

FIG. 8 is a cross sectional view taken along lines 8-8 in FIG. 2.

1 Claim, 7 Drawing Sheets
